Primary Examiner — Karen S Acker*Assistant Examiner* — Elizabeth S Ko(74) *Attorney, Agent, or Firm* — Maginot, Moore & Beck LLP(57) **CLAIM**

The ornamental design for a screwdriver, as shown and described.

DESCRIPTION

FIG. 1 is a perspective view of a screwdriver showing our new design;

FIG. 2 is a top plan view of the screwdriver of FIG. 1;
FIG. 3 is a bottom plan view of the screwdriver of FIG. 1;
FIG. 4 is a front side elevational view of the screwdriver of FIG. 1;

FIG. 5 is a rear side elevational view of the screwdriver of FIG. 1;

FIG. 6 is a left side elevational view of the screwdriver of FIG. 1; and,

FIG. 7 is a right side elevational view of the screwdriver of FIG. 1.

The broken lines shown in the drawings illustrate portions of the screwdriver that form no part of the claimed design.

1 Claim, 7 Drawing Sheets(56)
